A. Blodgett,
Attorney.

UNITED STATES PATENT OFFICE.

HARRY HANSON, OF WATERTOWN, MASSACHUSETTS, ASSIGNOR TO SELECT SERVICE COMPANY, OF BOSTON, MASSACHUSETTS, A VOLUNTARY ASSOCIATION.

AUTOMATIC COAT, HAT, AND UMBRELLA RACK.

1,412,939.

Specification of Letters Patent. Patented Apr. 18, 1922.

Application filed March 25, 1920. Serial No. 368,624.

To all whom it may concern:

Be it known that I, HARRY HANSON, a citizen of the United States, and a resident of Watertown, in the county of Middlesex and Commonwealth of Massachusetts, have invented certain new and useful Improvements in Automatic Coat, Hat, and Umbrella Racks, of which the following is a full, clear, and exact specification.

10 The object of this invention is the construction of an improved coin-controlled means for supporting a person's hat, coat and umbrella until such time as it is unlocked, the setting of the device and the removal of its key being only possible after the introduction of a predetermined coin.

In the drawings forming part of this specification, Fig. 1 is a front elevation of a device embodying my improvements. Fig. 20 2 is a front sectional elevation. Fig. 3 is a side sectional elevation. Fig. 4 is an under view of the coat lock. Fig. 5 is a horizontal section of the case showing the umbrella holding device.

25 I prefer to mount the operative mechanism of this device in a comparatively shallow case designed to be secured to a supporting wall or partition, and consisting of a back 1, sides 2, 3, a top 4, a bottom 5 and a front 30 6, a portion of the latter being frequently provided with a mirror 7.

Within this case and adapted for easy vertical reciprocation is a rod 10 reaching from the bottom 5 out through the top 4, being given a resilient upward movement when freed from the bolt 11 of the lock 12, such bolt engaging a notch 13 in the side of the bar, and the upward pull being given by a helical spring 14 attached to a finger 15 projecting from the bar, and to the case top 4. From this bar 10 project all the locking devices for the hat, coat and umbrella.

The hat shielding means consists of a yoke 16 rigidly supported by the case, the supporting means comprising an arm 17 screwed to the case, as shown in Fig. 3; and a locking yoke 19 connected by means of a goose neck 20 to the upper extremity of the bar 10, this neck being provided in order to allow room for the rim of the hat which is to be hung upon the yoke 16.

The coat hanger consists of a knob 21 rigidly connected by a neck 22 to the case front 6, and a movable locking cap 23 which is 55 united by a neck 24 to the laterally pro-

jecting arm 25 shown in Fig. 2, the case front having a vertical slot 26 to permit the cap to move vertically with the bar 10. As shown in Fig. 4, this cap is provided with a plurality of spring fingers 27 each fastened 60 at one end to the interior of the cap and projecting radially inward therefrom.

The umbrella holder consists of a pair of pivoted hooks 30 adapted to receive the handle of an umbrella when separated, but to 65 be pressed together and to lock the umbrella therein when the bar 10 is depressed. This locking action is performed by means of the finger 31 projecting from the bar 10 as shown in Fig. 2, and engaging and spread- 70 ing the tails 32 of the hooks 30.

To prevent the bar 10 being depressed without the introduction of the designated coin, a spring hook 33 is attached to the bar and adapted to engage a fixed stop 34 when 75 no coin has been put in, but when a coin 35 is dropped into the chute 36 and rests between the chute-throat 37 and the spring 33, a lowering of the bar 10 will cause the coin to press the spring hook out of the way of 80 the stop 34 and so permit the bar to be pulled down and the garments thereby to be locked in place.

The operation of this device is as follows: The key being in the lock 12 and incapable 85 of being withdrawn so long as the bolt 11 cannot be thrown toward either extreme, and the bar 10 being in its uppermost position, as illustrated by Fig. 2, then the yoke 19 will be a substantial distance above the stationary yoke 16, the cap 23 will be a suitable distance from the knob 21 and the umbrella holder will be open.

Then the user's hat, either a derby or a soft hat, is hung upon the stationary yoke 95 16, his coat is hung upon the knob 21 and his umbrella handle inserted between the hooks 30.

But the locking hook 33 holds the bar 10 from being drawn downward by means of 100 the hook 39 projecting from the cap 23. Upon the introduction of the proper coin in the chute 36, however, the bar 10 can be depressed until its notch 13 is in line with the bolt 11, the yoke 19 has descended into locking contact with the outer surface of the hat, the spring fingers 27 are strongly pressing the coat collar down upon the knob 21, and the finger 31 causes the hooks to lock the umbrella in place.

The key is now turned, throwing the bolt 12 into the notch 13 and permitting the key to be withdrawn. Upon the reintroduction of the key at any subsequent time and its turning, the bolt is disengaged from the notch 13, the bar 10 and its attached parts fly upward, and the various articles can be removed.

10 The spring fingers 27 I find to be most important features, inasmuch as they securely hold upon the knob 21 a garment of any thickness, from a heavy overcoat to a thin alpaca coat or a vest, and ensure the same against unwarranted removal so long as the bar 10 is locked down.

15 A further purpose of this rack is the retention of rubbers and the like. For such purpose, a horizontal arm 40 is rigidly supported parallel with and spaced from the bottom of the case by means of a neck 41, and pivotally attached to the case-bottom is a hand 42 adapted to swing from and toward the end of the arm 40, a spring 43 acting normally to hold the hand away. Above the 20 pivot 44 is an oblique short arm 45 adapted to be met by a projection 46 at the lower end of the bar 10 and to be forced in a direction

to press the hand 42 firmly against the end of the arm 40.

25 A pair of rubbers, gaiters or the like having been nested one into the other are suspended by their heel-ends upon the horizontal arm 40, so that when the other articles are locked in place by the lowering of the bar 10, the hand 42 will be swung against 30 the rubbers and thereby made to lock them securely in place.

35 In the same manner, a bag or other apertured article can be hung upon the arm 40 and locked thereon.

40 What I claim is:

An article support comprising a supporting member, a knob held thereby for receiving a garment thereon, a domed member having a semi-circular recess within it, movable 45 toward and from said knob, and spring fingers carried by said domed member to project radially inward, said fingers being yieldingly pressed upon said knob when the domed member is moved toward it.

50 In testimony that I claim the foregoing invention, I have hereunto set my hand this 23rd. day of March, 1920.

HARRY HANSON.
